UNITED STATES PATENT OFFICE.

NICHOLAS KRAMER, OF CHICAGO, ILLINOIS.

UMBRELLA-STAND.

1,013,662.

Specification of Letters Patent.

Patented Jan. 2, 1912.

Application filed July 27, 1911. Serial No. 640,893.

To all whom it may concern:

Be it known that I, NICHOLAS KRAMER, a subject of the Emperor of Austria-Hungary, residing at Chicago, in the county of Cook 5 and State of Illinois, have invented certain new and useful Improvements in Umbrella-Stands, of which the following is a specification, reference being had therein to the accompanying drawing.

10 This invention relates to umbrella stands especially designed for use in hotels, restaurants and other public places, and the primary object of my invention is the provision of novel means for temporarily locking 15 an umbrella, whereby it cannot be removed from the stand without an inspection of the umbrella, thereby preventing persons from accidentally removing umbrellas without ascertaining that the same is their property. 20 Another object of this invention is to provide an umbrella stand with a drip pan for collecting the drainings of umbrellas, thereby preventing the drainings from injuring a carpet, or forming a pool of water upon 25 a floor.

A further object of this invention is to provide an umbrella stand that is simple in construction, durable, neat in appearance and highly efficient for the purposes for 30 which it is intended.

With the above and other objects in view, the invention resides in the novel construction, combination and arrangement of parts to be hereinafter specifically described and 35 then claimed.

Reference will now be had to the drawing, wherein:—

Figure 1 is a perspective view of a stand in accordance with this invention. Fig. 2 40 is a longitudinal sectional view of a portion of the stand, and Fig. 3 is a perspective view of a portion of a modified form of stand.

An umbrella stand in accordance with this invention comprises posts 1 connected 45 by a lower longitudinal bar 2 and upper longitudinal bars 3 and 4, these elements providing a rectangular vertical frame that is preferably made of tubing with the lower ends of the posts provided with feet 5 and 50 the upper ends thereof with ornamentations 6. The bars 2, 3 and 4 have the ends thereof connected to the posts 1 by T connections 7 and 8, and connected to the connections 7 are the rear ends of supports 9, said supports having the forward ends thereof bent

inwardly with the lower ends of the posts 1 and provided with feet 10.

The bars 3 and 4 are provided with wire holders soldered or otherwise connected to the bars 3 and 4. Each holder comprises a split loop 11 having one end thereof bent inwardly, as at 12 and downwardly at an angle, as at 13 to the bar 3, it being preferable to insert the end of the wire in an opening 14 provided therefor in the bar 3. 60

Arranged upon the supports 9 at a point removed from the posts 1 is a drip pan 15 having a flared mouth 16 and a bottom plate 17 that inclines toward the center of the drip pan, which is provided with a central 70 opening 18. The bottom plate 17 is secured to the supports 9 by screws or other fastening means 19. The bottom plate 17, intermediate the ends thereof, is provided with drawer cleats 20 for the flanged edges 21 of 75 a drawer or receptacle 22 adapted to receive drippings from the pan 15. The forward end of the drawer or receptacle 22 has a handle 23 whereby it can be easily removed from beneath the drip pan 15. 80

After the lower end or tip of the umbrella is placed in the pan 15, the stick or handle is then inserted in the holder and when the umbrella is in the foregoing position it is obvious that it is prevented from 85 being quickly removed as the stick is compelled to be shifted from out of the holder before the umbrella can be removed.

In Fig. 3 of the drawing there is illustrated a slight modification of the invention, wherein the bar 4^a is provided with a holder 11^a that is made of a single piece of metal festooned or bent to provide open holders in which the sticks or handles of umbrellas can rest. 95

The umbrella stand in its entirety can be made of light and durable metal, enamelled or otherwise finished to present a neat appearance. 100

What I claim is:—

An umbrella stand comprising a pair of vertically disposed posts, inverted angle shaped supports projecting forwardly from the lower ends of said posts, a drip pan mounted upon the forward portions of said supports and spaced from said posts, a pair of superposed parallel bars connecting the upper portions of said posts together below the top thereof, a series of forwardly projecting split loops secured to the front por- 105 110 115

tion of the upper of said bars and spaced from each other, one end of each of said loops bent inwardly to extend parallel with the upper of said bars, said inwardly extending portions of a length substantially half the diameter of the loop and providing forwardly thereof a side entrance opening for the handle of an umbrella and further providing in connection with the rear portion of the loop a reduced space for the reception of the handle of the umbrella when the latter extends upwardly and rear-

wardly at an inclination with the tip thereof in the drip pan, said inwardly extending portions terminating in downwardly and rearwardly inclined portions connected to the front of the lower of said bars. ¹⁵

In testimony whereof I affix my signature in the presence of two witnesses.

NICHOLAS KRAMER.
